UNITED STATES PATENT OFFICE.

WILLIAM H. SCOTT, OF ST. LOUIS, MISSOURI, ASSIGNOR TO THE CONTROLLER COMPANY OF AMERICA, OF ST. LOUIS, MISSOURI, A CORPORATION OF MISSOURI.

COIN-CONTROLLED LOCKING MECHANISM.

SPECIFICATION forming part of Letters Patent No. 766,396, dated August 2, 1904.

Application filed July 21, 1902. Serial No. 116,405. (No model.)

To all whom it may concern:

Be it known that I, WILLIAM H. SCOTT, a citizen of the United States, residing at St. Louis, Missouri, have invented a certain new and useful Improvement in Coin-Controlled Locking Mechanisms, of which the following is a full, clear, and exact description, such as will enable others skilled in the art to which it appertains to make and use the same, reference being had to the accompanying drawings, forming part of this specification, in which—

Figure 1 is a longitudinal elevation showing the casing in section. Fig. 2 is a transverse sectional elevation. Fig. 3 is a sectional plan view on the line 3 3 of Fig. 1; and Fig. 4 is a top plan view, partly in section, on the line 4 4 of Fig. 2.

My invention relates to coin-controlled locking mechanisms, and more particularly to mechanisms of this character employed for the purpose of telephone-locks, the primary object of my invention being to provide a simple and efficient mechanism which employs but a single movable part for the purpose of locking the suspension-hook, the inserted coin coöperating with said movable part in such manner that the suspension-hook can be unlocked.

A further object of my invention is to provide a mechanism of the character indicated with means whereby when the suspension-hook has been unlocked and the receiver removed therefrom said suspension-hook can be thrown into lowered position at the will of the operator (as for the purpose of signaling central) without effecting relocking of the said hook until the receiver is again placed on the hook.

To these ends and also to improve generally upon devices of the character indicated my invention consists in the various matters hereinafter described and claimed.

Referring now more particularly to the drawings, 1 indicates a telephone-box, which can be of any suitable construction, and 2 represents the customary suspension-hook for the usual telephone-receiver 3. A box or casing 4 is secured to the wall or other suit-

able support, as by means of bolts or screws passing through the openings 4^a, and said casing extends at the side of the said telephone-box in such manner that the hereinafter-mentioned locking-bar lies over the said suspension-hook, said casing containing the herein-described locking mechanism and being provided with a coin-raceway 6 and also with a horizontal slot 7 in its bottom wall, suitable guides 8 preferably extending from said slot. A locking-bar 9 is substantially vertically slidable in said slot and between said guides, said bar being provided in its upper portion with a recess having a substantially vertical portion 10 and an angular portion 11 communicating with the upper end of said portion 10, thus producing a shoulder 12, which in the normal position of the locking-bar lies under a suitable stop or pin 13. This pin is preferably provided with a head 14, by means of which the slide-bar is guided in its movements. The portion of said slide-bar which lies above the part of said bar which extends downwardly from the said slot 7 extends inwardly—i. e., toward the hereinafter-mentioned coin-receptacle—thus producing a shoulder 14^a, which preferably rests upon the bottom wall of the casing when the slide-bar is in lowermost position. The portion of the slide-bar above that part of said bar which extends downwardly from the slot 7 extending upon the inner side of said portion which extends downwardly from the slot 7, the preponderance of weight is upon the inner side of the bar, whereby gravity not only throws the bar into lowermost position, but also throws the upper end of the same inwardly, the extent of inward movement of the bar being of course limited by the guides 8, the shoulder 14^a, and the pin 13. Preferably the desired downward and inward movement of the slide-bar is assisted by means of a light coiled spring 15, suitably secured to the slide-bar and to some relatively fixed member.

The upper end of the slide-bar lies in the line of the raceway 6 and forms, in effect, the bottom of said raceway, the casing being provided with suitable portions, as the stop mem-

bers 16 and 17, which when the slide-bar is in normal locking position permit a coin to seat between the member 16 and the upper inner corner of the slide-bar, the said members 16 and 17 preventing any substantial movement of the coin until the same has been released by the slide-bar.

Normally the slide-bar is in lowermost position above the receiver suspension-hook with 10 the shoulder 12 below the pin 13, so that the receiver suspension-hook is locked against upward movement. Upon the insertion of a coin or token α the said coin comes to rest between the upper inner corner of the slide-bar and 15 the stop members 16 and 17, as heretofore explained, and as the coin is held in a vertical position its curved edge presents a cam-surface which is engaged by the said corner of the slide-bar. As soon, therefore, as the telephone-receiver is removed from the suspension-hook the usual spring controlling said hook forces the hook upwardly and lifts the slide-bar, the cam-surface afforded by the coin throwing the bar outwardly sufficiently to 20 permit the shoulder 12 to clear the pin 13, and thus permit full upward movement of the slide-bar. As the bar continues to move upwardly its upper inner corner is carried above the periphery of the coin, and the support for 25 the coin being thus removed said coin or token drops into a suitable coin-receptacle 18. When the receiver is again placed upon the suspension-hook, said hook is lowered in a well-understood manner and the slide-bar falls into 30 normal locking position.

Pivottally supported upon the casing is a supporting-lever which has a downwardly-extending arm 19, to which the pivotal connection is made, and a substantially horizontal 40 arm 20, which extends beneath the receiver suspension-hook, said arm being provided with a curved finger or other part 21, adapted to be engaged by the receiver. When the receiver is in position upon the suspension-hook, it engages the said finger 21, and thus forces the same backwardly against the tension of a spring, which can conveniently be the heretofore-mentioned spring 15, one end of said spring being secured to the arm 19 of 45 the locking-bar-controlling lever and the other end being secured to the locking-bar. The arm 19 of the lever is provided with a nose or other suitable projection 22, which when the receiver is in position on the suspension-hook 50 lies at the side of the locking-bar and out of line therewith. When, however, the receiver is removed from the suspension-hook, the spring 15 rocks said lever upon its pivot and throws the nose 22 against the slide-bar, said 55 nose being thrown under the heretofore-mentioned shoulder 14 α as soon as the slide-bar has been sufficiently elevated. If, then, the suspension-hook is depressed while the receiver is removed from the same, the locking-bar 60 merely falls until the said shoulder 14 α

engages the said nose 22, such position being indicated by the dotted lines in Fig. 1 and the parts being so proportioned and arranged that when the locking-bar is so supported upon the said nose the shoulder 12 is above 70 the pin 13. Therefore as soon as pressure is removed from the receiver suspension-hook the said hook and the locking-bar are free to be again elevated by the usual spring which operates said hook. When, however, the operator again places the receiver upon the suspension-hook, said receiver engages the finger 21 and rocks the lever into the position shown by full lines in Fig. 2, the nose being carried from under the shoulder 14 α and the slide-bar 80 being thus permitted to fall into locking and locked position. In order to prevent the operator from accidentally engaging the arm 19 of the locking-bar-controlling lever when it engages the receiver suspension-hook for the 85 purpose of reciprocating the same, I provide a guard-web 23 upon the casing, said web lying at the side of and projecting beyond the arm 19 of the said lever when the same is in such position that the nose 22 is under the 90 shoulder 14 α .

Of course the locking slide-bar has sufficient play in its guides to permit the heretofore-described movements.

I am aware that many minor changes in the 95 construction, arrangement, and combination of the several parts of my device can be made and substituted for those herein shown and described without in the least departing from the nature and principle of my invention. 100

Having thus described my invention, what I claim as new, and desire to secure by Letters Patent, is—

1. In a mechanism of the character indicated, a casing provided with a bearing, a locking member guided by said bearing and bodily movable upon the same in two lines which are at an angle to each other, a stop in the path of movement of said locking member in the direction of normal movement of the latter 105 from locking position, and means for supporting a coin in said path of movement of said locking member to present the edge of said coin as a deflecting-surface for said locking member whereby as said locking member 110 moves in one line it engages the edge of the coin and is bodily deflected in the other line and thus caused to clear said stop; substantially as described.

2. In a mechanism of the character indicated, a casing having a passage producing a coin-raceway, a locking member which is bodily longitudinally movable and laterally deflectable, a stop in the path of longitudinal movement of said locking member toward unlocking position, said locking member, when in locking position, obstructing a portion of said coin-passage, whereby the periphery of a deposited coin strikes said locking member and said coin seats upon a corner of the same, 125 130

a coin-arresting device spaced from said corner and coöperating with the same to produce the coin-seat, and a second coin-arresting device spaced from the said coin-seating portion 5 of said locking member in the general direction of longitudinal movement of the latter toward unlocking position, whereby said second coin-arresting device and said coin-seating portion of said locking member lie upon 10 opposite sides of a deposited coin and, in the longitudinal movement of said locking member toward unlocking position, said locking member engages said coin and is thus deflected to clear said stop; substantially as described.

15 3. In a mechanism of the character indicated, a locking member which is bodily movable in two lines at an angle to each other and is provided with an angular guide-slot, a stop in said slot and in the path of normal movement of the shoulder produced by the angle of the same, and means for supporting a deposited coin in position to present a deflecting-surface to said movable member; substantially as described.

20 4. In a mechanism of the character indicated, a substantially vertically movable and laterally deflectable locking-bar having a laterally-projecting portion near its upper end whereby said bar tends to fall toward locked 25 position, said laterally-projecting portion being provided with an angular guide-slot whose angular extension projects away from the side of said bar provided with said laterally-projecting portion, a stop in said slot and above 30 the shoulder produced by the angle of the same, and means for supporting a deposited coin in position to present a deflecting-surface to said locking-bar to cause the said bar to be deflected to clear said stop; substantially as 35 described.

40 5. In a mechanism of the character described, the combination with the telephone-receiver and its movable suspension-hook of a longitudinally-movable locking-bar, which, 45 when in locked position, engages and locks said suspension-hook, means for locking said locking-bar, against movement, means for re-

leasing said locking-bar, a supporting-lever having one arm movable in and out of the path of movement of said locking-bar, and 50 adapted when in said path of movement to support the latter in released position and having a portion for engagement with the receiver when the latter is upon its hook, and yielding means common to both the supporting-lever and the locking-bar, and exerting tension on both the lever and locking-bar, in substantially a common plane, whereby when 55 said receiver is removed from said hook, said supporting-lever is automatically turned into 60 supporting position and capable of engaging said supporting-lever to hold it out of the path of movement of the locking-bar, substantially as described.

6. In a mechanism of the character indicated, a movable member adapted to lock a telephone-receiver suspension-hook, means for releasing said member, mechanism for maintaining said member in released condition during the time the receiver is removed 70 from the hook, said mechanism including a movable part adapted to lie in proximity to the said hook, and means for preventing the operator from engaging said part when he engages the said hook; substantially as described. 75

7. In a mechanism of the character indicated, a movable member adapted to lock a telephone-receiver suspension-hook, means for releasing said member, mechanism for maintaining said member in released condition during the time the receiver is removed from the hook, said mechanism including a movable part adapted to lie in proximity to the said hook, and a guard-web for preventing the operator from engaging said part 85 when he engages the said hook; substantially as described.

In testimony whereof I hereunto affix my signature, in the presence of two witnesses, this 3d day of July, 1902.

WILLIAM H. SCOTT.
